United States Patent Office

Des. 225,925
Patented Jan. 16, 1973

225,925

CHAIR

Gordon L. Duern and Donald S. Griffin, Kitchener,
Ontario, Canada, assignors to Electrohome Limited,
Kitchener, Ontario, Canada

Filed Apr. 7, 1971, Ser. No. 132,247

Term of patent 14 years

Int. Cl. D6—02

U.S. Cl. D6—69

FIG. 1

FIG. 2

FIG. 1 is a perspective view of a chair showing our design, looking down obliquely from the front and to one side; and

FIG. 2 is a perspective view of the chair of FIG. 1, as seen from the point in space opposite the viewpoint of FIG. 1.

We claim:

The ornamental design for a chair, as shown.
